Assistant Examiner — Kathleen L Jones

(57) **CLAIM**

The ornamental design for a micro AR gas tube, as shown and described.

DESCRIPTION

FIG. 1 is a top front perspective view of a micro AR gas tube showing my new design;

FIG. 2 is a bottom front perspective view thereof;

FIG. 3 is left view thereof;

FIG. 4 is a right view thereof;

FIG. 5 is a top view thereof;

FIG. 6 is a bottom view thereof;

FIG. 7 is a front view thereof; and,

FIG. 8 is a back view thereof.

The broken lines showing pipe openings are included for the purpose of illustrating portions of the article and form no part of the claimed design.

1 Claim, 8 Drawing Sheets
